UNITED STATES PATENT OFFICE.

WILLIAM HARGROVE AND JAMES JOHN WYLDE, OF MONTREAL, CANADA;
SAID HARGROVE ASSIGNOR TO SAID WYLDE.

IRONING-BOARD.

SPECIFICATION forming part of Letters Patent No. 633,837, dated September 26, 1899.

Application filed April 27, 1899. Serial No. 714,746. (No model.)

To all whom it may concern:

Be it known that we, WILLIAM HARGROVE and JAMES JOHN WYLDE, subjects of the Queen of Great Britain, residing in Montreal, Province of Quebec, and Dominion of Canada, have invented a new and useful Improvement 5 in Ironing-Boards, (for which we have obtained Letters Patent in Canada, No. 62,216, dated January 5, 1899,) of which the following is a full, clear, and exact description.

The object of the invention is to provide a new and improved ironing-board which is simple and durable in construction, readily attached to a table or like support without 15 danger of accidental displacement thereon, and arranged to permit of conveniently folding it and storing it in a comparatively small space when not in use.

The invention consists of novel features and 20 parts and combinations of the same, as will be fully described hereinafter and then pointed out in the claims.

A practical embodiment of the invention is represented in the accompanying drawings, 25 forming a part of this specification, in which similar characters of reference indicate corresponding parts in all the views.

Figure 1 is a side elevation of the improvement as applied. Fig. 2 is an enlarged perspective view of the bracket. Fig. 3 is an 30 enlarged perspective view of part of the leg. Fig. 4 is an enlarged sectional side elevation of part of the board, the bracket, and leg; and Fig. 5 is an enlarged inverted plan view 35 of the strengthening-plate.

The improved ironing-board is provided with a board A, proper, at the under side of which is screwed, bolted, or otherwise secured a bracket B, having a downwardly and transversely extending flange B' and depending lugs B², formed on their opposite faces with inclined bearings B³ for receiving the trunnions C², formed on the cylindrical portion C' of a leg C, adapted to rest at one end on 40 the floor, as is plainly illustrated in Fig. 1. The bracket B is arranged near the head end of the board A, and the portion of the head beyond said bracket is adapted to rest on the top of the table D, engaged at its under side 45 directly opposite said head portion by a clamping extension C³, formed integrally on the

cylindrical part C' of the leg C and extending at an angle to the latter, the top surface being corrugated, so as to securely clamp the under side of the top of the table D and hold 55 the board A against accidental movement or displacement while in use.

On the leg C, near the lower end thereof, is pivoted a brace E, the upper free end of which engages one of a series of teeth F', formed on 60 the under side of a strengthening-plate F, preferably made T-shaped, a cross-piece F² being transverse to the board A to prevent the same from warping. On the brace E is also secured a rubber cushion G, adapted to 65 rest on the leg C when the brace is not in use to prevent the leg from being marred by the brace when the latter is folded upon said leg.

On the leg C, near its pivotal end, is formed a transversely-extending lug C⁴, adapted to 70 rest in front of the depending flange B' to prevent accidental disengagement of the trunnions C² and the leg C from the bearings B³ at the time the device is in use, as will be readily understood by reference to Figs. 1 75 and 4.

In using the device the head end of the board A is placed on the top of the table, and the leg C, fulcrumed in the bearings B³, is then 80 swung downward and rests with its free end on the floor, engaging with its clamping extension C³ the under side of the top of the table D directly opposite the head of the board A to securely fasten the board in position, said board being then held in an extended or horizontal position by the operator engaging the brace E with a corresponding tooth F' of the strengthening-plate. When it is desired to 85 disengage the ironing-board from the table D, the operator disengages the free end of the 90 brace E from the plate F by slightly lifting the board A, and then the leg C is swung upward to swing the clamping extension C³ downward and out of engagement with the top of the table D to allow of removing the board 95 and leg from the table. The operator then swings the leg C downward to clear the lug C⁴ from the flange B' and permit of now sliding the trunnions C² out of the angular bearings B³ upon pushing the leg C in the direction of said bearings. The leg C is thus disconnected from the board A, and the latter, 100

with the leg C, having the brace E folded thereon, can now be readily stored away in a comparatively small space.

From the foregoing it is evident that the device is very simple and durable in construction, can be readily and conveniently attached to a table or like support whenever it is desired to use the board A for its legitimate purpose, and when so applied the ironing-board is not liable to be disconnected from the table or moved out of position while in use.

We do not limit ourselves to the exact construction shown and described, as it is evident that the same can be varied without departing from our invention.

Having thus fully described our invention, we claim as new and desire to secure by Letters Patent—

1. An ironing-board, comprising a board proper, a bracket secured to the under side thereof and having open bearings, a supporting-leg having trunnions adapted to be removably placed in said open bearings, said leg also having a clamping extension, a lug on said leg to normally hold it in an operative position, a strengthening-plate secured to the under side of said board proper, and a brace pivotally connected to said leg, the free end of the brace being adapted to engage one of a series of teeth formed on said strengthening-plate, substantially as shown and described.

2. An ironing-board, comprising a board proper adapted to rest at one end on a table or other support, a bracket attached to the under side of said board and having open bear-

ings and a downwardly-extending flange, a supporting-leg having trunnions for removably engaging said open bearings, the leg also having an angular clamping extension for engaging the under side of the support directly opposite said end of the board, said leg also having a lug for engaging said flange, to prevent accidental disconnection of the leg and bracket when the board is in use, and a brace between said supporting-leg and said board, substantially as shown and described.

3. In an ironing-board, the combination of a board proper, a bracket attached thereto and having depending lugs formed with bearing-grooves in their adjacent faces, a leg having trunnions adapted to slide and to turn in the bearing-grooves, the leg also having a lug serving to engage the bracket when the leg is in position, to prevent the displacement of the trunnions, a brace adapted to bear between the leg and board proper, and a clamping extension moving with the leg.

4. The combination of an ironing-board, a bracket attached thereto and having depending lugs formed with grooves therein, and a leg having trunnions capable of sliding and turning in the grooves, the leg also having a lug serving to engage the bracket when the leg is in place, to prevent the sliding of the trunnions.
